UNITED STATES PATENT OFFICE.

CHESTER C. KASKELL, OF NEWARK, NEW JERSEY, ASSIGNOR TO L. BAMBERGER & COMPANY, OF NEWARK, NEW JERSEY.

COIN-BOX.

1,391,063.

Specification of Letters Patent. Patented Sept. 20, 1921.

Application filed December 11, 1920. Serial No. 429,907.

To all whom it may concern:

Be it known that I, CHESTER C. KASKELL, a citizen of the United States, and a resident of Newark, county of Essex, and State of New Jersey, have invented certain new and useful Improvements in Coin-Boxes, of which the following is a specification.

This invention relates to an improved coin box which receives rolls of coins, usually of various denominations, the box being constructed so that when the box is opened the coins lie in channels or grooves and can be quickly removed therefrom and, if necessary, the required number extracted without unnecessary delay, and furthermore, one in which, when the box is closed and transported, and perhaps shaken about, the rows or rolls of coins are not disturbed, and when the box is again opened the coins are still in alinement.

This form of box is particularly adapted for use in department stores and like establishments where money is distributed to cash registers and the like, and where speed and facility of operation are essential requirements.

The invention is illustrated in the accompanying drawing, in which Figure 1 is a perspective view of the box opened. Fig. 2 is a vertical section of the box closed. Fig. 3 is a detail perspective view of a transverse partition used in the box, and Fig. 4 is a perspective view of a corrugated sheet used in the center of one of the lids.

The device consists of two members which are separable, these members being preferably in the form of lids 10 and 11 which are hinged together, as at 12, this being for convenience. The lid 10 is provided with a transverse partition 13 which is arranged near the outer or free end of the lid, as the other lid is swung upward and away from the person operating the box, and the space or chamber 14 between the end wall 15 and the partition 13 forms a compartment for the placing of loose odd pieces of coin or other articles.

The partition 13 is fastened in any usual way, as by soldering or the like, and is usually made of sheet metal having a flange 16 on each end which provides means for securely fastening the ends of the partition 13 in place. The side walls of the lid 10 extend all around the lid, and extending longitudinally of the lid, and at right angles to

the partition 13, are channels or grooves 17 which are preferably constructed by the installation of a corrugated or fluted plate of metal 18, the corrugations being of the required size to hold various sizes of coins, these being arranged in rows, as they are usually taken from rolls used commercially, particularly in retail establishments. The sides of the convolutions of the plate 18 are usually extended no higher than the lid.

The lid 11 has a marginal flange and has a central piece which is corrugated or fluted, as at 19, and is securely fastened to the lid and arranged opposite the channels 17 other than those alongside the side edges of the lid 10. In the form shown there are four grooves or channels in the lid 10, and these require but two convolutions in the plate 19, so that when the lids are closed the piece 19 confines the coins in the two central grooves 75 in the lid 10 and also co-operates with the side flanges or walls 20 of the members in inclosing the coins in the flanking or outside coin grooves.

The partition 13 extends above the side walls 20 of the lid 10, and thus when the lid 11 is closed down on the lid 10 the partition extends across the part 19, in fact fully closes the upper or outer end of all the coin grooves, as will be clearly seen from Fig. 2. Any suitable clasp 21 can be employed, which fits over a receiving member 22 to lock the lids in their closed positions.

This box has been found to be very desirable and to avoid vexatious delays in rearranging coins, and also in their transportation from one place to another, especially in the transportation of money, by cashiers, from a central office to cash registers in departments of department stores, its use in conjunction with such and other money counting machines being highly desirable.

I claim:

1. A coin box comprising two lids hinged together, the inner face of one lid having a set of grooves including a pair of central grooves and end grooves, and a corrugated sheet forming grooves arranged on the other lid to register with the central grooves on the first mentioned lid, each lid having marginal flanges to abut when the lids are closed.
2. A coin box comprising two lids hinged together, the inner face of one lid having a set of grooves including a pair of central grooves and end grooves, and a corrugated sheet forming grooves arranged on the other lid to register with the central grooves on the first mentioned lid, each lid having marginal flanges to abut when the lids are closed.

sheet forming grooves arranged on the other lid to register with the central grooves on the first mentioned lid, each lid having marginal flanges to abut when the lids are closed, 5 the grooves terminating short of the free ends of the lids, and a transverse partition in one lid forming the outer ends of the grooves and projecting so as to close the ends of the grooves on the second lid when the lids 10 are closed.

3. A coin box comprising one member having a transverse partition near one end and having parallel channels for holding rolls of coins, said channels extending longitudinally 15 of said member, the sides of the channels ex-

tending no higher than the sides of the member, the partition extending above the sides of the member, a second member having channels opposite the channels of the first member and extending no higher than 20 its sides, whereby when the members are assembled the channels are completely closed at the sides and the ends of the channels in both members are closed by the partition, the space beyond the partition forming a single 25 closed chamber.

In testimony that I claim the foregoing, I have hereto set my hand, this 10th day of December, 1920.

CHESTER C. KASKELL.
